ATTYS

UNITED STATES PATENT OFFICE.

PEMBER W. MORROW, OF VENICE, CALIFORNIA.

SAFETY GUARD FOR CONTAINERS.

Application filed October 26, 1922. Serial No. 597,223.

To all whom it may concern:

Be it known that I, PEMBER W. MORROW, a citizen of the United States, residing at Venice, in the county of Los Angeles and 5 State of California, have invented new and useful Improvements in Safety Guards for Containers, of which the following is a specification.

This invention relates to safety devices 10 and more particularly to a device for rendering difficult the opening of bottles or other containers holding poisonous matter.

It is an object of the invention to provide 15 a simple, practicable, and efficient device for use in combination with bottles and containers used for holding poison, and it is a broad object of the invention to provide means for preventing accidental use of a material from 20 a poison bottle, such as is a common occurrence with disastrous results.

Other objects and advantages will be made manifest in the following specifications of 25 an embodiment of the invention illustrated in the accompanying drawings wherein:

Fig. 1 is a front elevation of the device in 30 the bottle stopper releasing position.

Fig. 2 is a vertical, central section of the device.

Fig. 3 is a plan.

Owing to the frequency with which poison-containing bottles are wrongly selected, 35 the present invention is devised for the purpose of reducing the number of such accidents, and the device consists of a suitable

pan or box 2, of any suitable dimensions so as to conveniently receive a bottle 3. Upstanding from a side of the box 2, is a column or post 4, and slidably, adjustable along 40 this post is a hood or guard consisting of a cap 5, which is adapted to be shifted down into a position over the neck and stopper 6, of the bottle.

Means are provided for automatically 45 latching or locking the adjustable cap 5, in a restraining position over the neck of the bottle so that the bottle cannot be removed or unstoppered without first removing the guard or cap 5. The cap is shown as having a rearwardly extending sliding forming part 7, through which the post 4, extends, and within the slide, suitably ar-

ranged thereon, is a spring 8, so fashioned or operative as to draw a portion of the slide 7, into locking engagement with the post 4. The post is shown as of channel 55 form and has toothed edges 9, engaged by contiguous edges of the slide 7. The spring 8, serves to hold the slide in locking engagement with the teeth 9, until finger pressure is applied to the slide in such manner as to 60 disengage the locking teeth 9, after which the slide and the cap 5, can be shifted upwardly to release the bottle.

From the above it will be seen that I have provided a simple and effective device for 65 substantially locking poison containing bottles so that access cannot be inadvertently had thereto.

Further embodiments, modifications and variations may be resorted to within the 70 spirit of the invention as here claimed.

What is claimed is:

1. Means for preventing accidental selection of a poison bottle, comprising a receiver for the bottle and a device combined with 75 the receiver and adapted to be shifted into fastening position over the neck and the stopper of the bottle.

2. Means for preventing accidental selection of a poison bottle, comprising a receiver 80 having a base for the bottle and a slide combined with the receiver and adapted to be shifted into fastening position over the neck and stopper of the bottle, and preventing the removal of the stopper from the bottle. 85

3. Means for preventing accidental selection of a poison bottle, comprising a receiver for the bottle and a slidible device combined with the receiver and adapted to be shifted into fastening position over the neck of the 90 bottle, and toothed locking means for holding the said device in its set position.

4. A device for preventing accidental selection of a poison bottle, comprising a bottle receiver, an upright at one side of the receiver, a slide mounted on the upright and having means for preventing access to the stopper of the bottle, and means for automatically locking the slide in set position. 95

In testimony whereof I have signed my 100 name to this specification.

PEMBER W. MORROW.
